UNITED STATES PATENT OFFICE.

ROSS C. COMINGORE, OF SIOUX FALLS, SOUTH DAKOTA.

ADJUSTABLE CARD HOLDER.

1,412,168.

Specification of Letters Patent. Patented Apr. 11, 1922.

Application filed May 14, 1921. Serial No. 469,607.

To all whom it may concern:

Be it known that I, Ross C. COMINGORE, a citizen of the United States, residing at Sioux Falls, in the county of Minnehaha 5 and State of South Dakota, have invented certain new and useful Improvements in Adjustable Card Holders, of which the following is a specification.

This invention relates to improvements 10 in display card holders.

The primary object of the invention is the provision of an adjustable holder for receiving various sizes of display cards; and for properly supporting the same for observation.

A further object of the invention is the provision of a display card holder of the above described character, which embodies certain easily adjustable and novel extension 20 means for preventing a card from buckling; and to present said card at an angle to the vertical, for display purposes.

A further object of the invention is the provision of a show card holder of the above described character, which is artistic in appearance, yet simple in construction, and consequently one which can be manufactured at a relatively small cost.

Other objects and advantages will be apparent during the course of the following detailed description.

In the accompanying drawings, forming a part of this specification, and in which similar reference characters designate corresponding parts throughout the several views,

Figure 1 is a perspective view of the improved card holder, showing various details thereof.

Figure 2 is a side elevation of the improved card holder.

Figure 3 is a fragmentary enlarged view of certain details of the improved card holder, and showing the cooperating relation 45 thereof.

Figure 4 is a front elevation showing the improved card holder, holding a standard size show card.

Figure 5 is a front elevation of the card holder showing the same supporting a standard size card, of different dimensions from that illustrated in Figure 4.

Figure 6 is a front elevation, showing the improved card holder supporting a standard size show card, of different dimensions

than the cards illustrated in Figures 4 and 5.

In the drawings, wherein for the purpose of illustration is shown the preferred embodiment of my invention, the letter A designates a standard, having means B detachably and adjustably mounted thereon, said means B supporting card engaging members C. An extension unit D is provided for connecting said members C.

The standard A is preferably of artistic design, including a polygonal shaped base 10, formed of upwardly arcuated and converging sides 11, to present a pyramidal appearance. Suitable lugs, or legs 12 are provided upon the bottom of base 10 to properly support the same. A polygonal shaped supporting rod 13 is provided integral with the base 10, extending upwardly therefrom in a vertical position. It is preferred that 70 the base 10 and rod 13 be of some approved metal to provide an artistic finish.

An upper supporting arrangement 15, comprising part of the supporting means B is provided, and includes a sleeve 16 having a central aperture therein polygonal in formation, and for adjustably receiving the polygonal shaped shank 13 of the standard A.

A suitable clamping screw or bolt 17 is provided on one side of the sleeve 16 for 85 engaging a side of the rod 13, to maintain the sleeve 16 in any supported position on the rod 13. A suitable extension 18 is provided upon one side of the sleeve 16, and preferably diametrically opposite the set 90 screw 17. The arm 19 is riveted or otherwise secured upon this extension 18, and arranged in vertical and parallel relation with the rod 13 of the standard A. The arm 19 is provided upwardly thereof with lateral 95 extensions 20^a, for a purpose to be subsequently set forth.

A lower supporting arrangement 20, comprising a part of the supporting means B, is provided for disposition upon the standard 100 13, below the upper supporting arrangement 15. The supporting arrangement 20, includes a sleeve 21 of identical formation as the sleeve 16; said sleeve 21 including a clamping bolt 22 for adjustment of the sleeve 105 21 on the rod or standard A. An extension 23 is provided upon the sleeve 21 to receive a supporting arm 24 as by riveting or the like. The supporting arm 24 comprises a vertical portion 25 adapted for attachment 110

directly to the extension 23, and is preferably provided with a downwardly inclined portion 26, bent upon the vertical portion 25 and extending at an acute angle, downwardly, to the horizontal. A third portion 27 of the arm 24, is inclined in such position as to lie in substantially the same plane as the lugs 20 upon the upper end of the upper arm 19. By this arrangement, the lower arm 24 extends outwardly from the standard A for a farther distance than the upper arm 19.

The upper and lower members C are identical in formation, being substantially U-shaped in cross section, to provide a channel arrangement, whereby a groove 30 is provided in each of the members C, for receiving a display card E. The members C may be of any approved type of material, however, preferably of some artistic appearing metal, such as nickel, polished brass, or the like; which arrangement is desirable, in view of the fact, that a forward leg 31 of each of the members C is visible, when the card E is supported in the grooves 30. An upper member C is mounted centrally of its length, by attachment of the lugs 20 of the arm 19, to the rear leg 32 of said upper member C, as by rivets 33 or the like. In this position, the groove 30 of the upper member C faces downwardly toward the lower arm 24, and preferably at an acute angle to the vertical. The lower member C is similarly riveted or secured to the inclined portion 27 of the arm 24; the groove 30 of the lower member C, facing to be in alignment with the groove 30 of the upper member C; and which arrangement likewise positions the lower member C at an acute angle to the vertical. Thus, if a display card E were to be inserted in the grooves 30 of the upper and lower members C, the card so inserted would be supported at an inclined position as defined by the members C; and which inclined position would be at an acute angle to the vertical position as defined by the standard A. Suitable slots 35 are longitudinally arranged in the rear legs 32 of the members C, and adjacent each outer end of said members C, the purpose for which the slots 35 are provided will be subsequently set forth.

Since the members C are so positioned as to arrange a display card E at an inclined position, which ordinarily would be an acute angle to the vertical, it can be seen that if such show card E would be flexible (as is ordinarily the case), said show card E would buckle, or crimp, and would probably not of its own inherent tendency be supported in the groove 30 of the members C. In order to properly support the show card in the members C, the expandable unit D is provided, simulating in appearance the ordinary lazy tong arrangement. The expandable unit D includes a plurality of expandible

links 40, certain of said links 40 being centrally connected by pivots 41, to arrange said links 40 in pairs. Any number of the links 40, of course can be employed, it being a requisite in constructing the expansion unit D that the ends of the links 40 be pivotally connected, as at 42, to provide the ordinary lazy tong arrangement. In order to provide for relative movement between the links 40 and the members C, the upper and lower links 40 are provided upon their outer ends with suitable rivets or extensions 45, adapted to project into the slots 35 in the rear legs of the members C, and are secured in any suitable manner therein for reciprocation. The expansion of unit D is necessarily provided, due to the fact that the members C are adjustably positioned with respect to each other, upon the standard A. Thus, as the lower member C would be moved toward the upper member C, the links 40 of the unit D would be pivoted upon their various pivoting points, and the relation of the various links 40 would be changed. Likewise, the extreme ends of those links 40 adjacent the members C would move relative to said members; which movement would be permitted due to the fact that the extensions or rivets 45 on those particular links 40 are reciprocable in the slots 35 of members C.

From the foregoing, it can be seen that a card holder has been provided, in which the upper and lower supporting arrangements 15 and 20, respectively have been provided, whereby show or display cards of various sizes can be accommodated. Due to the polygonal formation of the standard A there will be no liability of oscillation of the members C thereabout. A card E will be maintained in its inclined position at an acute angle to the vertical, and which is a desirable arrangement with modern show card display; this being effected without any liability of buckling of the card, and which is primarily effected by the support given by the expandable unit D.

Changes to the shape, size and arrangement of parts may be made to the form of the invention herein shown or described, without departing from the spirit of the invention or the scope of the claims.

I claim:

1. A card holder, comprising in combination, a vertical standard, card engaging members, arms adjustably connecting said members to said vertical standard to support a card in a plane at an acute angle to the axis of said standard, and an extension unit connecting said card engaging members.

2. A card holder, comprising in combination a standard, card engaging members adjustably supported on said standard, and an extension unit, said card engaging mem-

bers having slots therein to receive portions of said extension unit, to permit relative movement between said members and said extension unit.

- 5 3. A card holder, comprising in combination, a standard, upper and lower card engaging members, an arm adjustably positioned on said standard, and supporting said upper member, a second arm adjustably
- 10 mounted below said first mentioned arm to support said lower member on said standard and projecting outwardly from said standard farther than said first mentioned arm, whereby said members can support a card
- 15 at an angle inclined to the vertical.
4. A card holder, comprising in combination a pair of card engaging members having slots therein, an extension unit comprising a plurality of pivotally connected links, 20 certain ends of said links being reciprocably disposed in the slots of said members to permit relative movement between the card members and the extension units for supporting various sized cards.
- 25 5. A card holder, comprising in combination a pair of channel shaped card engaging members, said card engaging members each having a leg thereof provided with longitudinal slots adjacent its ends, an extension unit 30 comprising a plurality of pivotally con-

nected links in lazy tong formation, certain free ends of said links having extensions thereof for disposition in the slots of said members to permit relative movement between the card engaging members and the 35 extension unit for supporting various sized cards.

6. A card holder, comprising in combination a base, a polygonal shaped stem arising therefrom; an upper supporting arrangement mounted on said stem, said upper supporting arrangement including a sleeve adjustably clamped to said stem, and an upwardly extending vertical arm; a lower supporting arrangement mounted on said 40 stem and including a sleeve adjustably mounted on said stem, and an outwardly and downwardly inclined supporting arm mounted on said stem of said sleeve, said lower supporting arm extending outwardly 50 farther than said upper supporting arm, with respect to said polygonal shaped stem; channel members mounted on said upper and lower supporting arms; and an expansible unit pivotally connected intermediate said channel shaped members, and expansible upon adjustment of said upper and lower supporting arrangements with respect to each other.

ROSS C. COMINGORE.
